UNITED STATES PATENT OFFICE.

WILLIAM KOTHE, OF THOMPSONVILLE, CONNECTICUT.

SHUTTLE-BINDER FOR LOOMS.

SPECIFICATION forming part of Letters Patent No. 373,896, dated November 29, 1887.

Application filed March 7, 1887. Serial No. 230,152. (No model.)

To all whom it may concern:

Be it known that I, WILLIAM KOTHE, a citizen of the United States, residing at Thompsonville, in the county of Hartford and State 5 of Connecticut, have invented new and useful Improvements in Shuttle-Binders for Looms, of which the following is a specification.

This invention relates to shuttle-binders for looms, and to that class thereof which are pivoted; and the invention consists in the peculiar construction and arrangement of the binder and of the several parts thereof, all as herein-after fully described, and pointed out in the claim.

15 In the drawings forming part of this specification, Figure 1 is a perspective view of an ordinary loom shuttle-box having applied thereto a shuttle-binder embodying my improvements. Fig. 2 is a side elevation of a portion of the 20 binder. Fig. 3 is a longitudinal section of that part of the binder shown in Fig. 2, showing, in dotted lines, one position of the hinged end of the binder.

This invention is in the nature of an improvement upon the construction shown and 25 described in Letters Patent issued to me January 9, 1883, No. 270,228, the object of the herein-described improvements being to provide an improved hinge-connection between the 30 body of the binder and the piece which is connected to its free end, whereby said piece is capable of vibrating from as well as toward the shuttle, and whereby the said hinged piece is capable of such adjustment with relation to 35 its operating-spring as cannot be easily deranged by those working on a loom to which the binder is attached.

A further object of the improved construction herein shown is to provide a simplified 40 hinged connection between the binder and its said hinged end-piece.

In the drawings, 3 indicates the shuttle-box 45 of a loom, and 4 the shuttle-binder, which is pivotally connected by one end at *n* to the shuttle-box, whereby the binder is capable of a certain vibratory motion in a horizontal plane. The said binder is constructed, preferably, of malleable iron, to obviate the danger of breakage in the use to which it is subjected.

50 A spring, 6, is attached by one end to the side of the shuttle-box, as shown, and its free end

has a bearing against the side of the binder, whereby the latter is held yieldingly in a certain position opposite the vertical side of the shuttle-box.

55

The free end of the binder 4 is slotted, as shown, to permit of the introduction between its bifurcated parts of the end of the hinged extension-piece *c*, a pivot-pin, *x*, being passed transversely through said bifurcated parts and 60 the end of said piece *c*, whereby the latter is hinged or pivoted to the end of the binder, the latter having formed therein a socket, *e*. The socket *e* is adapted to receive a spiral spring, *o*, one end of which bears against the base of 65 said socket, and a plunger, *v*, having one end cylindrical, is placed within said spring, the outer end of the latter bearing against a shoulder on said plunger, as shown. The outer end of the plunger *v*, as well as the end of the 70 socket *e*, in which it operates, are of rectangular form, in order that the plunger may be prevented from turning in said socket. The face of the outer end of the plunger *v* is at right angles to its axis, and the end of the aforesaid 75 hinged extension-piece *c*, against which the end of said plunger is forced by said spring *o*, is at right angles to its inner face, so that the normal position of said hinged piece *c*, when solely under the control of the plunger *v* and the 80 spring *o*, is that shown in the drawings, the dotted lines in Fig. 3 showing the position of said hinged piece when swung toward the vertical side of the shuttle-box. When the hinged extension-piece *c* is struck by a moving part, 85 *a*, Fig. 1, of the loom, whereby it is swung toward the vertical side of the shuttle-box, a certain resistance to said swinging movement of said piece *c* is supplied by the spring *o* through the plunger *v*, which is driven endwise against 90 said spring by the engagement of the end of the piece *c* with the end of said plunger, and the degree of resistance which said spring offers to the deflection of the hinged extension *c* toward the shuttle 5, when the latter is between 95 the binder and the opposite side of the shuttle-box, determines the retaining force of the binder to keep the shuttle in its place in the box for a certain time. In constructing the binder and connecting thereto its said hinged extension-piece the desired strength of the 100 spring *o* is definitely fixed upon, and after it

is inserted in the socket in the binder, together with the plunger *v*, and the piece *c* is secured to the end of the binder by the pin *x*, which is riveted thereto, the parts must remain in their operative relations, thereby insuring the action of the said extension-piece *c* under a regulated resistance, a derangement of said parts being difficult owing to the permanency of their connection, as above described, whereas in my said patent a loom-operative might, to the detriment of the proper operation of the device, change the resistance to the vibratory movement of the extension-piece of the binder by turning the nut on the end of the bolt *f* of said patent.

I have found in practice that for the better protection of the binder against injury by loom-operatives it is advisable to provide a hinged connection between the extension-piece *c* and the body of the binder, which permits said extension-piece to swing outwardly or away from the shuttle-box as well as toward it, for the reason that said operatives, under the impression that the binder should, for some reason, be curved more than it ordi-

narily is toward the shuttle, attempt to bend the binder by striking it when the shuttle or some other object is between the extension-piece *c* and the opposite side of the shuttle-box; and if said extension-piece, under those circumstances, is rigid against any outward movement, as it is in my said patent, its hinged connection with the binder is likely to be broken or rendered inoperative, whereas, by means of the construction herein shown, any injury to the binder parts by such treatment is obviated.

What I claim as my invention is—

A shuttle-binder for looms, having a socket, *c*, in its free end, combined with the extension-piece *c*, hinged to the end of the binder and capable of vibratory motions thereon, the spring *o* within said socket, and the plunger *v*, entering said spring and having its end engaging the hinged end of said piece *c*, substantially as set forth.

WILLIAM KOTHE.
